UNITED STATES PATENT OFFICE.

ELLIOT D. FISHER, OF FRANKLINVILLE, NEW YORK.

DESIGN FOR A CAMPAIGN-BADGE.

SPECIFICATION forming part of Design No. 21,172, dated November 17, 1891.

Application filed October 20, 1891. Serial No. 409,332. Term of patent 7 years.

To all whom it may concern:

Be it known that I, ELLIOT D. FISHER, a citizen of the United States, residing at Franklinville, in the county of Cattaraugus and State of New York, have invented and produced a new and original Design for a Campaign-Badge, of which the following is a specification, reference being had to the accompanying drawings, forming a part thereof, in which—

Figure 1 is a face view, and Fig. 2 is an edge view, of a campaign-badge embodying my new design.

The design consists in the configuration and ornamentation shown.

The side marginal lines a a' are straight and parallel, and the end marginal lines b b' extend from the bottom a' upward the greater portion of the height of the badge, then out-

ward at right angles, and again outward and upward, joining the top marginal line a , which latter line extends at each end beyond the bottom line a' . On the face of the badge medallions c c appear, and between the same appears the representation of the United States flag. (Indicated by the letter d .) There also appear on the face of the badge the word "American" and the words "For President," "For Vice-President," but such words form no part of my design.

I claim—

The design for a campaign-badge herein shown and described.

ELLIOT D. FISHER.
